US00D543523S

(12) **United States Design Patent** (10) **Patent No.:** **US D543,523 S**
Lee et al. (45) **Date of Patent:** **** May 29, 2007**

(54) **MOBILE PHONE**

(75) Inventors: **Ja-Youn Lee**, Seoul (KR); **Bum-Soo Park**, Gwangmyeong-si (KR); **Jong-Seong Lee**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/233,504**

(22) Filed: **Jul. 6, 2005**

(30) **Foreign Application Priority Data**

Jan. 6, 2005 (KR) 30-2005-0000358

(51) **LOC (8) Cl.** **14-03**

(52) **U.S. Cl.** **D14/138**
